BUBBLE GUN

Nicholas J. Limber, Rockville Centre, N. Y., assignor to Bubble Gun, Inc., New York, N. Y., a corporation

Application June 17, 1946, Serial No. 677,198

8 Claims. (Cl. 46—8)

1

This invention relates to toys, and more particularly to a toy for producing bubbles.

It is the primary object of the present invention to provide a toy gun or pistol which fires bubbles in response to the action of a trigger.

It is another object of the present invention to provide a toy of this character with bubble-forming mechanism which is well hidden in a gun or pistol casing so that the appearance of the toy does not suggest its use as a bubble blower.

It is also among the objects of the present invention to make the toy from simple, inexpensive parts which are readily assembled, so that the toy lends itself to rapid mass production at low cost.

The above and other objects, features and advantages of the present invention will be fully understood from the following description, considered in connection with the accompanying illustrative drawings.

In the drawings:

Fig. 1 is a longitudinal section through the pistol embodying the present invention;

Fig. 2 is an elevational view, partly broken away, and in section, of the same pistol showing the bubble forming mechanism in action;

Figs. 3 and 4 are sections taken on the lines 3—3 and 4—4, respectively, of Fig. 1;

Fig. 5 is a longitudinal section through a pistol having a modified bubble forming mechanism;

Fig. 6 is a section taken on the line 6—6 of Fig. 5; and

Fig. 7 is a fragmentary longitudinal section through a pistol having a further modified bubble forming mechanism.

Referring to the drawings, and particularly to Figs. 1 to 4 thereof, the reference numeral 10 designates a toy gun or pistol which comprises a casing 12 formed to simulate a pistol, and a bubble-forming mechanism 14 in the casing 12.

The casing 12 is preferably formed of two complementary halves or sections 16, 16 which may be made from sheet metal. In assembled relation, the sections 16 are in edge to edge abutment as shown at 18 in Figs. 3 and 4. In order to hold the sections 16, 16 in their assembled relation, one of these sections 16 is preferably provided at its edge with spaced, laterally extending integral tabs 20 which are passed through adjacent slots 22 in the other section 16 and bent over in the fashion shown in Fig. 3. The inwardly formed, adjacent ends 24 of the sections 16 (Fig. 3) are provided with complementary cut-outs 26 which form a round discharge opening 28.

The bubble forming mechanism 14 has for its main elements an air blower 28, a bubble-form-

2

ing ring member 30, a tank 32 for holding any suitable solution 34 for producing bubbles, and a trigger element 36 for actuating the bubble-forming mechanism. The air blower 28 is, in the present instance, in the form of a rubber bulb 38 having a preferably integral tubular extension 40, the end 42 of which receives a preferably metallic nozzle 44. The end 42 of the tube extension 40 is suitably anchored in the pistol, as by means of a clamp 46 which embraces the tube end 42 within the confines of the inserted nozzle 44 and is suitably secured to one of the sections 16 (Fig. 3) by spot welding, for instance. The bulb 38 is preferably carried by the trigger element 36 by having its tubular extension 40 extended through holes 50 and 54 in a strap-like rearward extension 52 and another extension 55, respectively, of the trigger element 36, in such fashion that said tubular extension 40 is bent, rather abruptly, between said openings 50 and 54. The trigger element 36 is pivoted on a cross pin 56 which extends through the sections 16, 16 of the casing 12 and is preferably riveted over at its ends, thus further holding the sections 16, 16 together in their assembled relation. The trigger element 36 also has a downward extension 58 within the casing 12 on which the bulb 38 normally rests (Fig. 1).

The ring member 30, which may be of the shape shown in Fig. 4, is preferably punched from sheet metal stock. The ring member 30 is, in the present instance, of rectangular shape having a round aperture 60 and an upwardly extending shank 62 which is connected with operating linkage to be described hereinafter. The ring member 30 is guided for vertical movement in opposite guides 64 which are preferably in the form of U-shaped channels secured to the sections 16, 16 by spot welding or in any other suitable manner.

The tank 32 may be made from any suitable material and assume any desired shape to fit the general design of the pistol without suggesting its use as a tank. The tank 32 is mounted on the casing 12 for ready removal therefrom so that the same may be refilled whenever required. To this end, one side wall 70 of the tank 32 (Fig. 4) is provided with a slot 72 which receives an outwardly bent lug or tab 74 on one of the sections 16 of the casing 12, while the opposite side wall 76 of the tank is provided with a sunken bead 78 that is snapped over a raised bead 80 in the other section 16 of the casing 12. The tank 32 is removed from the casing 12 by simply turning the former counter-clockwise about the lug 74 as a fulcrum (Fig. 4), in order to unsnap the beads 78 and 80, whereupon the tank may readily be removed from the

lug 14 and refilled with solution. The refilled tank 32 may readily and quickly be remounted on the casing 12 by simply hanging the tank over the lug 14 on the casing and then forcing the tank against the casing until the bead 78 snaps over the bead 80. In order to minimize or prevent splashing of the solution from the tank 32 to the outside of the casing 12 as well as to the inside thereof, the open top of the mounted tank is closed by the adjacent wall 82 of the casing 12 which is recessed at 84 just sufficiently to clear the guides 64 and permit the passage of the ring member 30 to and from the tank 32.

The operating linkage between the trigger element 36 and the ring member 30 comprises a link 86, a bell crank lever 88 and a tension spring 90. More particularly, the bell crank lever 88 is pivotally mounted on a cross pin 92 which extends through the opposite section 16 of the casing 12 and is riveted over at its ends in the fashion shown in Fig. 3. One arm of the lever 88 is hingedly connected at 94 with the shank 62 of the ring member 30, while the other arm of said lever 88 carries a laterally projecting pin 96 on which one end of the spring 90 is anchored. The other end of the spring 90 is anchored on a laterally projecting pin 98 on one end of the link 86, the other end of which is pivotally connected at 100 with the trigger element 36. The anchor pin 96 on the lever 88 serves also as a support for the link 86 on which the same rests when the pistol is not in action. The trigger element 36 is normally urged into its forward position (Fig. 1) by means of a spring 102 which is anchored with one end on said trigger element and with the other end on a punched-out loop 104 on one of the sections 16 of the casing 12.

Fig. 1 shows the pistol with the bubble forming mechanism 14 in inactive position in which the ring member 30 is immersed in the solution 34 in the tank 32. In actuating the gun for shooting bubbles, the trigger element 36 is pulled or depressed inwardly, whereupon the ring member 30 is first raised from the tank 32 (Fig. 1) to the position shown in Fig. 2 in which the aperture 60 in the ring member is in operative alignment with the air discharge nozzle 44. The described ascent of the ring member 30 from the tank 32 into operative alignment with the air discharge nozzle 44 takes place during an initial part of the depression of the trigger element 36, through intermediation of the parts 86, 88 and 90, and the ring member comes to rest in its operative position when the bell crank lever 88 is conveniently stopped by the top wall 106 of the casing 12 (Fig. 2). Thereafter, and during continued depression of the trigger element 36, the fully expanded bulb 38, which has in the meantime been moved against the adjacent end wall 110 of the casing 12, is squeezed or partially collapsed between said end wall 110 and the adjacent extension 58 of the trigger element (Fig. 2), whereby air is discharged from the bulb 38 through the tubular extension 40 and the discharge nozzle 44. The nozzle 44 is provided in its front wall 114 with a multitude of perforations 112 in order to diffuse the air so that it will sweep evenly through the ring member 30 and cause the solution adhering thereto to form a bubble or bubbles 116 which issue from the discharge opening 26 in the casing 12 in a fashion similar to that shown in dot-and-dash lines in Fig. 2.

In order that the bulb 38 may quickly recover of its own accord when the depressed trigger 36

is released, the same is preferably made from relatively thick rubber or a similar elastic material which will recover its shape after being squeezed. The discharge opening 26 is sufficiently large in diameter so as to clear a bubble or bubbles forming at the aperture 60 in the ring member 30, in order to prevent bursting of the bubbles through contact with the casing 12. The guides 64 are sufficiently wide (Fig. 3), to guide the ring member 30 upwardly and downwardly despite its hinged connection 94 with the pivotally mounted bell crank lever 88. The instant gun is repeating in action until the solution in the tank 32 is exhausted, whereupon the latter is refilled.

Fig. 5 illustrates a bubble gun or pistol which differs from that shown in Fig. 1 by using a bellows 120 in lieu of a collapsible bulb for creating the air charge. The bellows 120 is suitably mounted with its discharge end in a bracket 122 which is, in turn, mounted in any suitable manner in the casing 124, the bracket 122 being constructed so as to leave the discharge end 126 of the bellows exposed. The discharge end 126 may be a rigid disk having a multitude of perforations (not shown) which serve to diffuse the air charge as it is forced from the bellows 120. The bellows is operated by means of a crank disk 128 and a connecting rod 130 between the latter and said bellows. More particularly, one end of the connecting rod 130 is pivotally connected by means of a pin 132 with the adjacent end of the bellows 120, while the other end of the connecting rod 130 is journaled on a crank pin 134 on the disk 128. In order to compel the bellows 120 to expand and contract longitudinally, the connecting pin 132 extends with its ends into opposite guides 136 which are preferably in the form of U-shaped channels and suitably secured, as by spot welding, to the adjacent sides of the casing 124 (Fig. 6). The crank disk 128 is carried by a cross pin or shaft 138 which is rotatably mounted in the opposite side walls 137 of the casing. The crank disk 128 is spring-wound by means of a torsion spring 140 (Fig. 6) which is anchored with one end in said crank disk and with its other end in one of the side walls 137 of the casing 124. The spring 140 is prewound in the sense that it will partially unwind on counter-clockwise rotation of the crank disk 128 (Fig. 5) through its operating range, and will be wound on opposite rotation of said crank disk. Unwinding of the crank disk 128 beyond its operating range is prevented by a pin 144 on said crank disk which cooperates with a punched-out stop lug 146 in the casing 124.

Mounted on a cross pin 148 in the casing 124 is a trigger 150, having a pawl-like extension 152 which is adapted to register with a notch 154 in the periphery of the crank disk 128 when the latter is wound up. A spring 155 normally urges the pawl-like extension 152 of the trigger 150 against the crank disk 128. Integral with, or carried by, the crank disk 128 is a cam element 156 which cooperates with the follower end 157 of a lever 158, rotatably mounted on a cross pin 160 in the casing 124 and hingedly connected at 162 with the ring member 30'. The cam element 156 is so designed and coordinated with the crank disk 128 that its crest 164 cooperates with the lever 158 in holding the ring member 30' immersed in the solution in the tank 32' when said crank disk is wound up. A spring 166 holds the lever 158 in permanent engagement with the cam element 156.

The crank disk 128 is wound up, through less than one revolution, by means of a key 168 (Fig. 6) which may have a square end, that fits into

a correspondingly shaped socket 170 provided on one end of the cross pin or shaft 138 on the outside of the casing 124. The key 168 may also be formed as an integral part of the shaft 138, if so desired.

In using the pistol, the crank disk 128 is wound-up by means of the key 168 until the pawl-like extension 152 of the trigger 150 snaps into the notch 154 in said crank disk to lock the latter in its wound position (Fig. 5). In thus winding the crank disk 128, the cam element 156 actuates the lever 158 so that the same lowers the ring member 30' and immerses it in the solution in the tank 32' (Fig. 5). The pistol is now ready for action and the trigger 150 may be pulled. In doing so, the pawl-like extension 152 of the trigger is withdrawn from the notch 154 in the crank disk 128, whereupon the latter unwinds to the extent permitted by the pin 144 and the stop lug 146. During an initial part of the unwinding motion of the crank disk 128 in the direction of the arrow A in Fig. 5, the cam element 156 permits a relatively rapid ascent of the ring member 30' from the tank 32' into operative alignment with the discharge end 126 of the bellows 120, during which time the crank pin 134 on the disk 128 passes to and beyond its remote dead center position X, with the result that the bellows 120 is relatively unaffected during this initial part of the unwinding motion of the crank disk. However, after the ring member 30' is in operative alignment with the discharge end 126 of the bellows 120, i. e., when the follower end 157 of the lever 158 rides on the concentric portion 172 of the cam element 156, the crank disk 128 passes through the remaining part of its unwinding range in which the connecting rod 130 is rapidly advanced and the bellows accordingly compressed for the discharge of air therefrom and through the operatively aligned ring member 30' for the formation of a bubble or bubbles thereat.

Fig. 7 shows a further modified pistol in which the air blower is in the form of a cylinder 180 having a piston 182 therein. The pistol may in all other respects be like the one shown in Fig. 5, except that the connecting rod 130' is connected to the piston 182. The cylinder 180 is mounted in any suitable manner on brackets 184 which are, in turn, suitably mounted in the casing 124'.

It will be understood that various changes in the details of construction and in the arrangement of parts may be made without departing from the underlying idea or principles of this invention within the scope of the appended claims.

Having thus described my invention, what I claim and desire to secure by Letters Patent, is:

1. A toy gun comprising, a casing resembling a gun and having a discharge opening and a container below said opening for holding a bubble-forming solution, means within said casing for forcing a stream of air through said opening, an apertured member within said casing lowerable into said container and raisable therefrom into the path of said air stream at said opening, and a device in said casing including an outwardly projecting trigger for successively raising said member and causing operation of said air-forcing means on the same manipulation of said trigger.

2. A toy pistol as set forth in claim 1, in which said air-forcing means is a resiliently collapsible rubber bulb, and said device partially collapses said bulb on manipulating said trigger.

3. A toy gun comprising, a casing resembling a gun and having a discharge opening and a container below said opening for holding a bubble-

forming solution, means in said casing for forcing a stream of air through said opening, an apertured member in said casing lowerable into said container and raisable therefrom into the path of said air stream at said opening, a spring-wound device in said casing for successively raising said member from said container and causing operation of said air-forcing means when said device unwinds, and a trigger projecting to the outside of said casing and having a latch normally holding said device in wound condition and releasing the latter when said trigger is depressed.

4. A toy pistol as set forth in claim 3, in which said air-forcing means is a bellows.

15 5. A toy pistol as set forth in claim 3, in which said air-forcing means is a cylinder and a piston therein.

6. In a toy gun, a casing having the shape of a simulated gun, and being provided with an 20 opening at the muzzle end thereof, said gun casing housing within it a container below said opening for holding a bubble-forming solution, pivoting means for forcing an air stream through said opening and lowering an apertured member 25 in said container and raising said apertured member into the path of said air stream at said opening, and a device including an outwardly projecting trigger for successively raising said member and causing operation of said member on manipulating said trigger whereby said air forcing means 30 operates to discharge air in delayed response to said trigger means after said raised member has been raised into the path of an air stream from said air-forcing means.

35 7. A toy gun as set forth in claim 6 in which said air-forcing means is a resiliently collapsible rubber bulb, and said device partially collapses said bulb on manipulating said trigger.

8. A bubble blower comprising a casing provided 40 with an opening for the passage of bubbles therefrom, an air conduit having an opening adjacent said casing opening, said casing having a reservoir for a bubble-forming solution disposed adjacent to and below said opening of said conduit, a member mounted in said casing for movement into and out of said reservoir and provided with an opening positioned to register with said conduit opening when said member is retracted from said reservoir, an air pump for forcing air through said conduit, and a device mounted on said casing and operatively connected to said member for moving the latter into and out of said reservoir and concomitantly out of and into registry with said conduit opening and having an operative connection with said pump for operating the latter to expel air through said conduit in timed relation to the movement of said member into registry with said conduit opening.

NICHOLAS J. LIMBER.
